AMUSEMENT RIDE

John R. Dyke, Eden, Ala.

Application January 20, 1939, Serial No. 251,985

6 Claims. (Cl. 272—17)

This invention relates to amusement rides of the type used at carnivals and other amusement places. One of its objects is to provide an amusement ride in which an oscillatory swing is mounted in a rotary cylinder or drum whereby persons seated in the swing will, due to the relative motion of the drum and the swing, have the sensation of far greater motion than that to which they are subjected.

10 Another object of the invention is to provide means associated with the cylinder or drum to heighten the illusion of motion.

Another object of my invention is to provide an amusement ride in which a rotatable cylinder 15 surrounds a swing and in which the swing may be swung back and forth by an operator standing outside the cylinder.

A further object of my invention is to provide an amusement device comprising a swing with 20 surrounding rotary cylinder in which all of the seats on the swing may be loaded from one door in the surrounding cylinder.

A still further object of my invention is to provide an amusement ride comprising a swing with 25 a surrounding rotary cylinder constructed of strong, durable and light parts which can be readily assembled and disassembled for transportation, and which will occupy a minimum of space when disassembled.

30 Briefly, my invention comprises a swing having parallel facing seats, the frame of which is made of structural steel members and the seats of which face each other. The swing is mounted for oscillation on stub shafts within a rotary cylinder which is also mounted for rotation on the stub shafts, and is rotatable independently of the swing. The cylinder is preferably covered with canvas or other translucent material and may have figures or stripes thereon which, when the cylinder is rotated, aid in affording the illusion of motion to the passengers. The swing is oscillated back and forth by a person standing 35 on the outside while at the same time the cylinder surrounding the swing may be turned. Light shining through the translucent covering of the cylinder with its light and dark stripes causes a person sitting in the swing to have the illusion of swinging much farther than he actually does with the sensation of a possibility of turning over 40 and over in the cylinder. Access to the swing within the cylinder is had through a side door which may be closed and locked when the device is in operation. When passengers are entering 45 the swing, it is locked against any motion.

50 55 Apparatus embodying features of my invention

is illustrated in the accompanying drawings forming a part of this application, in which

Fig. 1 is a side elevational view of the apparatus with a part of the covering removed to show the swing within the cylinder;

Fig. 2 is a detail sectional view of the support for one of the A-frame members;

Fig. 3 is a similar sectional view of the lower end of another of the A-frame members;

Fig. 4 is an end view of the apparatus;

Fig. 5 is an enlarged detail end view of the supporting shaft at one end of the cylinder;

Fig. 6 is a fragmental sectional view taken along the line VI—VI of Fig. 5;

Fig. 7 is a sectional view of the swing looking in the direction of the arrows VII—VII of Fig. 8;

Fig. 8 is a plan view of the swing;

Fig. 9 is a detail view showing the bearing support for the swing, together with the means 20 for connecting the crank thereto to operate it;

Fig. 10 is a fragmental sectional view taken on the line X—X of Fig. 9;

Fig. 11 is a detail view of the latch for closing the door giving access to the interior of the cylinder, taken along the line XI—XI of Fig. 1;

Fig. 12 is a detail view showing the construction of the longitudinal frame sections for the cylinder;

Fig. 13 is a detail end view of the rotary cylinder 30 frame; and

Fig. 14 is a sectional view taken along the line XIV—XIV of Fig. 13.

Referring to the drawings for a better understanding of my invention, I show parallel supporting sills 10 and 11 which extend the length of the apparatus. A-frames comprising outer members 12 and inner members 13 joined together by suitable cross braces 14 are mounted at each end of the sills 10 and 11. The A-frame members 12 and 13, as may be seen in Figs. 2 and 3, are formed from angle irons. The member 13, at its base, has welded thereon a supporting angle 15 which rests on top of the sill 11, while the flange of the angle 13 is bent to 40 fit against the side of the sill 11 and is joined to the sill by means of a bolt 16. The angle 12, at its base, has its flange 17 turned under the sill 11 and is joined to the sill by means of a bolt 18. The reason for this construction will be apparent, as the inner member 13 bears downwardly on the sills due to the weight of the parts supported thereby, and the outer member 12 pulls 45 upwardly. Mounted on the upper end of the A-frame members 12 and 13, by means of U-bolts 50 55

19 and 21, are hollow stub shafts 22 and 23. The A-frame members are joined together at the bottom by means of transverse members, such as 24, shown in Fig. 4.

5 Supported for rotation on the inner ends of the stub shafts 22 and 23 is a cylinder 26. The cylinder 26 is comprised of semi-cylindrical end frames 27 and 28, each made up of a plurality of segments of a circle. As may be seen in Fig. 13, 10 the periphery of each of the end frames is preferably made of angle iron, which may have its inwardly extending web notched at regular intervals and be bent to the desired shape and welded. Radial angles 29 and 31 are joined to 15 the ends of the respective halves of the end frame and are joined together by means of bolts 32. Radial angle members 33, 34, 35, and 36 join the peripheries of the halves of the end frame members at regular intervals and are in turn 20 joined, preferably by welding, to semi-cylindrical members 37 and 38 to form, when the halves are bolted together, the outer shell of the central hub for the cylinder 26. The construction at the two ends of the cylinder is identical, and the description 25 thereof need not be repeated.

The hub members 37 and 38 bear against and hold firmly between them a cylindrical member 39 which may be made from a standard dimension piece of pipe. Fitting within the member 39 30 and over the stub shaft 22, are two bearings 41 which are preferably ball bearings, and thus provide for easy rotation of the end frame members on the shafts 22 and 23.

The end frame members are joined together 35 by a plurality of rectangular frame members 42. The frame members 42 are made up of longitudinally extending angle members 43 and transversely extending angle members 44 which are welded together. The members 44 fit within the 40 angle members 27 of the end frame, as shown in Fig. 14, and are joined thereto by means of bolts 46. On one side of the cylinder there is provided a door 47, the frame of which is preferably made from steel rod 48 bent to the proper shape, and 45 hinged at the top by means of straps 49 and 51 to one of the longitudinally extending frame members 43. The members 45, which would otherwise cross the opening of the door 47, are cut short to form the opening and are joined to 50 the other longitudinally extending members, and to each other, by means of cross braces 52 and 53, which are bolted to the nearest members 43 extending the full length of the cylinder, as shown more particularly in Fig. 12. The members 43 are 55 joined together intermediate their ends by means of cross braces 54. The door 47 may be latched closed by means of a spring pressed catch 55, as shown in Fig. 11, which is secured to a cross member 54.

60 The cylinder 26 is preferably covered with a translucent covering, such as a fabric or the like, which permits a certain amount of light to pass through. It is preferably patterned with spaced dark colored stripes 57, which obstruct the light 65 and which give to a person inside the cylinder the illusion of motion when the cylinder is rotated. The covering may be detachably applied to the cylinder by means of snaps 58.

Disposed within the cylinder 26 is a swing 70 which is made up of similar end A-frames 59 made preferably from angles joined together at the top, as shown in Figs. 9 and 10, with a flange 61 extending over a ball bearing 62 which, at each end, surrounds the stub shafts 22 and 23. 75 Collars 60, on the inner ends of the stub shafts

22 and 23, prevent the A-frames 59 from shifting thereon. A collar 160 is placed around each of the stub shafts 22 and 23 between the A-frames 59, and the cylinder bearing 39, to prevent relative movement between the swing and the cylinder. A collar 161 on each of the shafts 22 and 23 aids in holding the cylinder in place thereon. A washer 162, between the collar 161 and the bearing, aids in holding lubricant in place. A plate 163 is welded across the A-frame members 59 to the inwardly extending flanges 61 thereof to afford additional strength and to hold the ball bearing 62 in place. Additional cross frame members 64, 65 and 66 are joined to the members 59 by welding, the members 65 and 66 extending laterally beyond the frame members 59, as shown in Fig. 7. Joined to the frame members 59 at the bottom by means of bolts 67, is a rectangular floor frame comprised of longitudinally extending channel members 68 and transverse channel members 69, which may be joined together at the corners by welding. A floor 71, preferably of wood, rests on the floor frame just described.

Extending upwardly at a slightly divergent angle, intermediate the ends, on opposite sides of the swing frame, are a plurality of channel members 72, which have their flanges cut away so as to join at the bottom, by means of bolts 73, to the longitudinally extending channels 69. At their upper ends, the channel members 72 have their flanges cut away and the web 74 turned over to fit about a pipe 76 which extends longitudinally of the swing to form the upper frame member of the swing. On the side of the swing where passengers are admitted, two pipes 77 and 78 fit within the curved end portions 74 of the channels 72 to form a gap to admit passengers to the swing, as seen in Fig. 8. Slidably mounted within the pipe sections 77 and 78 is a rod 79 which may be slid across the gap and secured in place by a pin 81, or the pin 81 may be removed and the rod slid out of the way to admit passengers when desired. The support of the swing by means of stub shafts also becomes important in that it permits the entrance and exit of the passengers from one side only of the swing. It has another important function in that the passengers do not see any relatively stationary object when occupying the swing, which would tend to lessen the illusion of motion created by the apparatus.

The angles 66, which extend across and are secured to the A-frame members 59, have their flanges turned inwardly of the swing to afford an end support for seats 82 and 83. Angle members 84 extend longitudinally of the swing and are secured to the channel 72 to afford a rear support for the seats 82 and 83. At each of the four corners of the swing a channel member 85 extends parallel to the members 72 and is joined to the ends of the angles 65 and 66 by means of bolts 86. The members 85, as will be seen in Fig. 7, are similar in all respects to the members 72 except they do not extend down to the floor of the swing. Suitable backrests 85 are provided and are secured in any suitable manner to the members 72 and 85. Extending along the front of the seats 82 and 83 are angle members 87 which rest at their ends and are bolted to the inturned flanges of the angle members 66 by means of bolts 90. The angle members 87 are supported intermediate their ends by diagonally extended braces 88, which are joined at their bases by welding to the members 72. As seen in 75

Fig. 8, the seat 82 is divided to permit the ingress and egress of passengers from the swing.

I have found that it greatly increases the value of my improved apparatus as an amusement ride to have the seats of the swing facing each other. In operation there is an illusion of motion to the extent that the passengers feel that the swing may turn over and over, whereas it may be moving only slightly. If the occupants of the swing face each other and see the expression on each other's faces during the operation of the apparatus, it greatly enhances its amusement value.

The swing may be operated by any suitable means, but is preferably operated manually by means of a crank 89 which extends through the hollow shaft 22 and is secured to the transverse member 64 by means of a U-bolt 91. At the outer end of the crank 89 is secured a downwardly depending arm 92 which may be grasped to operate the swing manually. Inasmuch as the swing is supported on the ball bearings 62, it may be readily swung back and forth by one man with as many as fifteen persons in the swing.

In order for passengers to enter and leave the swing, I provide on one side a set of steps 93 which are hinged at 94 to one of the longitudinally extending sills 11 so that they may be pivoted upwardly to the dotted position shown in Fig. 4. Secured to one of the members 63 intermediate its ends, is a plate 96 carrying an eye 97. Carried by the steps 93 is a plate 98 having eyes 99 which fit above and below the eye 97 when the steps are in raised position, in which position a pin 100 may be passed through the eyes 97 and 99 to hold the swing and steps rigidly against movement so that passengers may enter or leave the swing. In this position the cylinder 26 is held against rotation by means of a rod 105 pivoted to one of the frame members 13 and having a hook 106 on the end thereof adapted to engage with an eye 107 on the end of the cylinder. The adaptability of my improved device for loading and unloading the swing from one side only affords great economy of space in operation. This is very important, because concessions at amusement places are rented usually on the basis of the ground occupied. It will be seen that my improved ride occupies only half as much ground as would be necessary if passengers had to be loaded from both sides.

When the swing is being loaded or unloaded, the door 47 may be raised to its upper dotted position shown in Fig. 4, by any suitable means, such as a pulley and hook 101, and held in its raised position while passengers are entering and leaving the swing. When the swing is fully loaded, the bar 79 is secured in closed position, and the door 47 is let down and is fastened by means of the latch 56. The swing is then started to oscillate by an operator on the outside, while the cylinder 26 may be rotated either manually or by any other suitable means, not shown. Light shining through the translucent cover with its alternate dark colored stripes causes the occupants of the swing to have the illusion of turning over and over in the cylinder. The cylinder may be rotated for a while in one direction, and stopped and rotated in the opposite direction to heighten the illusion and direction of the motion. Since the swing and cylinder move with the stub shafts as a common center, whenever the swing is moving in the

direction of rotation of the cylinder the passengers see a fewer number of bars of light per unit of time through the covering than when the swing is moving opposite to the direction of rotation of the cylinder. I have found that this varying number of bars of light per unit of time heightens the illusion of motion much more than if the same number passed before the passenger's eyes at all times during the ride. When operated at night, as will be well understood light will be supplied from the outside to shine through the translucent covering. The fact that the swing is suspended from stub shafts becomes important for two reasons. Passengers may be loaded from one side only without having to stoop under the shaft. Also, the illusion of motion is heightened by reason of the fact that there is no stationary object for the passengers to see when seated in the swing.

Whenever it is desired to move the apparatus, the members comprising the swing frame may be disassembled where bolted together and packed in a very small space. The covering for the cylinder, being detachably secured by means of snaps or the like, may be removed and packed up. The longitudinally extending frame sections, comprised of the members 43, 44 and 45, are next unbolted from the end frame members, and the halves of the end frame members are disassembled. The main supporting A-frames 12 and 13 are then dismounted from the longitudinally extending sills 10 and 11, and the apparatus may be packed in a very small space for transportation. Its assembly is as simple and requires only a short period of time. This is very important, because apparatus such as hereinbefore described is usually operated only a few days at a time in one location, and its assembly, disassembly, and transportation constitute a large percentage of the cost of operation.

From the foregoing it will be apparent that I have devised an improved amusement ride which is simple of construction and operation, and which is economical of assembly, disassembly and transportation.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

What I claim is:

1. An amusement ride comprising a cylinder, longitudinally extending rectangular frame members for the periphery of the cylinder, diametrically divided end frame members detachably secured to the longitudinal members, a hub at each end of the cylinder detachably connected to the end frame members, a stub shaft for each hub terminating just inside the cylinder at each end, parallel A-frame members at each end of the cylinder for supporting the shafts and the cylinder, a swing extending longitudinally within the cylinder substantially the whole length thereof and supported from the ends of the stub shafts, means forming a door in the side of the cylinder giving access to the swing, a translucent longitudinally striped cover for the cylinder, and means to operate the swing from outside the cylinder.

2. An amusement ride comprising a cylinder, 75

longitudinal rectangular frame members for the periphery of the cylinder, diametrically divided end frame members detachably secured to the longitudinal members, a hub at each end of the cylinder detachably connected to the end frame members, a stub shaft for each hub terminating just inside the cylinder at each end, parallel A-frame members at each end of the cylinder for supporting the shafts and the cylinder, a swing 10 extending longitudinally within the cylinder substantially the whole length thereof and supported from the ends of the stub shafts, side and floor frame members for the swing detachably joined together, parallel seats for the swing 15 facing each other and extending longitudinally thereof, means forming a door in the side of the cylinder giving access to the swing, and a crank extending from outside the cylinder through one of the stub shafts for operating the swing.

3. An amusement device comprising a swing, seats on said swing facing each other, stub shafts at either end of said swing upon which the swing is rockably mounted, a rotatable cylinder mounted on said stub shafts enclosing said swing, a translucent cover for said cylinder, a series of horizontal alternately dark and light stripes on the cover of said cylinder, an entrance door on said cylinder, and means to rock said swing from without the cylinder.

4. In an amusement ride, a swing, longitudinal facing seats on the swing one of which is divided to provide an open section to give access to both seats, a stub shaft at each end of the swing from which it is suspended, a cylinder

mounted for free rotation on the stub shaft and surrounding the swing, means giving access to the interior of the cylinder and the swing opposite the division in said seat, and means to operate the swing from the exterior thereof.

5. In an amusement ride, a swing, longitudinal facing seats on the swing one of which is divided to provide an open section to give access to both seats, a stub shaft at each end of the swing from which it is suspended, a cylinder mounted for free rotation on the stub shaft and surrounding the swing, means giving access to the interior of the cylinder and the swing opposite the division in said seat, means to operate the swing from the exterior thereof, and a detachable fabric cover for said cylinder provided with alternate dark and clear stripes to give to persons in the swing the illusion of motion when the cylinder is rotated.

6. In an amusement ride, a swing, longitudinal facing seats on the swing one of which is divided to provide an open section to give access to both seats, a stub shaft at each of the swing from which it is suspended, a cylinder mounted for free rotation on the stub shaft and surrounding the swing, means giving access to the interior of the cylinder and the swing opposite the division in said seat, means to operate the swing from the exterior thereof, a detachable fabric cover for said cylinder provided with alternate dark and clear stripes to give to persons in the swing the illusion of motion when the cylinder is rotated, and parallel supporting A-frames for the stub shafts at each end of the cylinder.

JOHN R. DYKE. 35
